DISTRIBUTOR

Jakob R. Frei, Sidney, N. Y., assignor to Bendix Aviation Corporation, South Bend, Ind., a corporation of Delaware

Application October 8, 1940, Serial No. 360,227

8 Claims. (Cl. 200—21)

1

This invention relates to ignition apparatus, and more particularly to means for distributing electrical current from one or more sources of high tension electrical energy to a plurality of electrical circuits in a predetermined sequence such as in the ignition system of an internal combustion engine.

One of the objects of the present invention is to provide a novel ignition distributor wherein the insulating parts are less subject to damage 10 as a result of changes in temperature and during handling by personnel.

Another object of the invention is to provide novel rotatable means in a distributor for an ignition system having main and booster circuits 15 which comprises parts that may be readily assembled for rotation in either direction.

A further object is to provide a distributor which is adapted to be rigidly connected to both the engine casing and a shielding harness for 20 the outgoing and incoming electrical leads, necessary timing adjustments being made by adjustment of the rotatable element of said distributor with respect to the driving means therefor.

Still another object is to provide a novel distributor which is so constructed that the same is inherently radio-shielded without the addition of 25 special shielding parts.

A still further object is to provide novel ignition distributing means which is light in weight 30 and in which the more fragile parts and the parts having the shortest useful operating life are so constructed that the same may be readily and inexpensively replaced.

The above and further objects and novel features of the invention will more fully appear from the following detailed description when the same is read in connection with the accompanying drawings. It is to be expressly understood, however, that the drawings are for the purpose of 40 illustration only and are not intended as a definition of the limits of the invention, reference being had primarily to the appended claims for this latter purpose.

In the drawings, wherein like reference characters refer to like parts throughout the several views,

Fig. 1 is a side elevation, mostly in section and with parts broken away, of one form of distributor embodying the invention;

Fig. 2 is a top plan view, partly in section and with parts broken away, of the assembled rotatable contact or terminal carrying means of the distributor of Fig. 1;

Fig. 3 is a sectional view of said contact carrying means, the section being taken substantially on line 3—3 of Fig. 2;

Fig. 4 is a sectional detail view taken substantially on line 4—4 of Fig. 2; and

Fig. 5 is a detail view, partly in section and

2

with parts broken away, showing the novel ventilating means of Fig. 1 on an enlarged scale.

A single embodiment of the invention is illustrated in the drawings, by way of example, in the form of an ignition distributor which is particularly adapted for use in a radio-shielded ignition system such as is now in common use on aircraft engines. In the form shown, the current carrying elements of the distributor are housed, supported and radio-shielded by a three-part metallic casing comprising a base portion 10, a central or body portion 11, and a cover 12. Casing member 10 which is cup-like is provided with a central opening 13 in which a rotatable shaft is journaled and is adapted to be rigidly secured to an engine casing or the like (not shown) by bolts which extend through a plurality of openings 14. Body portion 11 is cylinder-like in construction and is adapted to be removably secured to base portion 10 by means of a plurality of stud bolts 15, a lateral wall 16 intermediate the ends of said body portion forming the top of a chamber 17 in which the rotating parts of the distributor operate. Cover 12 is removably secured to the upper end of body 11 by set screws 18 or other suitable means and forms the top of a second chamber 19 above wall 16. Body portion 11 may also be provided with an opening 20 in the side thereof for the passage of cables from chamber 19 to a radio-shielding harness manifold 21 (only partly shown), which may be of the character illustrated in Spengler et al. copending application Serial No. 271,220, or any other suitable type.

For the purpose of rendering the present distributor capable of use in its entirety with engines regardless of the required direction of rotation of the rotatable elements thereof, for the purpose of making it unnecessary to shift the distributor casing angularly for timing purposes, and for the further purpose of reducing the number of failures and delays due to fracture of the molded insulating parts, a novel rotatable mechanism is provided. In the form illustrated, said mechanism comprises a beveled ring gear 22 adapted 35 to be driven by the engine with which the distributor is associated, said gear having a sleeve-like hub portion 23 extending into the inner race of ball-bearings 24 which are mounted in a sleeve 25 having a drive fit in opening 13. A plate 26 40 of metal or other suitable material in chamber 17 is provided with a downwardly extending sleeve-like hub portion 27 which is freely journaled in the upper end of hub 23.

In order to drivably connect gear 22 and plate 55 26 together, whereby the former may directly drive the latter and yet provide for small angular adjustments of one with respect to the other, an adjustable coupling is provided which comprises a bolt 28 that has a free sliding fit in hub 27 50 and splined engagement, as at 29, with hub 23

of gear 22. The inner face of head 30 of said bolt has an annular series of ratchet teeth 31 cut thereon that mesh with a similar set of teeth 32 cut on the upper surface of a ring or sleeve 33 which freely surrounds bolt 23 for free angular and axial movement relative thereto. The lower face of ring 33 is likewise provided with a series of ratchet teeth 34 which have a slightly different pitch than teeth 31, 32 and mesh with a similar set of ratchet teeth 35 cut on rotating element 26, 27. In one commercial embodiment, the diameter of head 30 is .695" and there are 24 teeth on one face of ring 33 and 23 teeth on the other face thereof. By making a shift of one tooth in each set of meshing teeth and in opposite directions, an angular adjustment equal to the difference in the pitches of the two sets of teeth may be accomplished, i. e., an adjustment of less than one degree. The teeth 31, 32 and 34, 35 are normally held in mesh, so that gear 22 and plate 26 will rotate as a unit, by a nut 36 threaded onto bolt 23 and engaging the lower face of said gear. When nut 36 is loosened sufficiently to permit the making of an adjustment, a spring 37 yieldably holds the ratchet teeth 31, 32 and 34, 35 in mesh. These teeth are so cut that when plate 26 is turned in one direction teeth 31 and 32 tend to slip over one another, while teeth 34 and 35 tend to slip over one another when said plate is turned in the opposite direction. Thus, when nut 36 is loosened, oscillation of either plate 26 or gear 22 to the extent of one ratchet tooth in each direction effects a very small angular adjustment between said gear and plate. When nut 36 is tightened against gear 22, a direct drive is formed from said gear through splines 29, ratchet teeth 31, 32, ring 33, and ratchet teeth 34, 35 to plate 26. It is believed that a more detailed showing or description of the adjustable coupling is not necessary since it does not per se constitute a part of the present invention.

Mounted on plate 26 for rotation therewith are novel means for picking up current from stationary supply leads and distributing said current in a predetermined manner to a plurality of terminals or electrodes to be later described, said means being adaptable for rotation in either direction, less subject to breakage, and more readily and inexpensively replaced than similar means heretofore provided for the same purpose. As illustrated, said means comprises two molded insulating blocks 38 and 39 secured to plate 26 for rotation therewith by bolts 40 and 41, respectively (Fig. 2), and preferably separated from said plate by a spacer plate 42 of insulating material. Block 38 has a central metallic terminal 43 embedded therein and projecting beyond the upper surface thereof, which is connected by an embedded wire 44 to a disk or contact 45 that is fixed in said block intermediate the ends of a cylindrical passage 46 through the block, the opposite ends of said passage constituting coaxial recesses. Also embedded in block 38 adjacent the periphery thereof is a metallic ring 47 which extends beyond the upper surface of the block and is connected by a lead 48 to a contact disk 49 fixed in a through passage 50 that is parallel and diametrically opposite passage 46.

Electrode carrying block 39 is secured to plate 26 adjacent one end thereof and has a pair of spaced terminals or electrodes 51 and 52 embedded therein and projecting outwardly beyond the periphery thereof, as best seen in Fig. 2.

The embedded ends of said electrodes form the inner ends of cylindrical recesses 53 and 54, respectively, which are in axial alignment with passages 46 and 50 of terminal block 38. For electrically connecting electrodes 51 and 52 to terminals 45 and 49, a pair of connectors 55 are provided. Said connectors slidably extend into said recesses and passages and may be constituted by short lengths of insulated cable, each having a coil spring 56 secured to each end thereof. To insure smooth rotation of the rotating parts, the insulating block 38 is balanced by a counterweight 23a which may be integral with plate 26.

If it is desired to connect terminals 51 and 43 and terminals 52 and 45, i. e., the reverse of the connections illustrated in the drawings, it is only necessary to turn terminal block 38 through 180° relative to plate 26, it being noted that said terminal block is symmetrically constructed with respect to a plane parallel to passages 46 and 50 and containing the axis of rotation of plate 26. Thus, either electrode 51 or 52 may be readily connected to either ring terminal 47 or center terminal 43 of block 38. This reversability results from making the contact carrying elements 38 and 39 in two parts instead of one and this, in turn, results in the ready and inexpensive replaceability of electrodes 51 and 52 when the same become corroded or burned. Also, by making the molded insulating parts smaller in size and with less embedded metal, there is less danger of said parts becoming cracked or broken during manufacture and use, which often occurs by reason of the different coefficients of expansion of the insulating and metallic parts and the shrinkage of the molded insulating material during the drying process.

High tension current supplied to terminal 43 in a manner to hereinafter appear is distributed during rotation of plate 26 and the parts mounted thereon to a plurality of circularly arranged terminals or electrodes that are connected with ignition devices and which are constructed and mounted in casing member 11 in a novel manner to minimize the possibility of damage and reduce to a minimum the weight of the complete unit, the initial cost and the cost of repair in case of accidental damage. As shown, each of said terminals consists of a conductor 57 embedded in a molded insulator 58, which extends through and has threaded engagement with metallic wall 16. The ends of each conductor 57 may be counterbored and threaded for receiving terminal screws 59 and 60. Each of a plurality of cables 61 is connected to one of the annularly arranged conductors 57 and is led out of chamber 19 through opening 20 into shielding harness manifold 21, from whence it is connected, either directly or through other connecting cables, to a spark plug of the engine on which the distributor is used. The lower ends of terminals 57, 59 are preferably wholly within casing 11, i. e., above the lower edge thereof as shown in the drawings, to thereby minimize the danger of damage to said terminals when the structure is disassembled.

High tension current from any suitable source of supply (not shown), such as a magneto, is conducted to the distributor through a cable 62 which also enters chamber 19 from harness 21 or other suitable inlet and is connected to a central terminal 63 that is similar both in mounting and construction to terminals 57, 58, except that the lower end of the conducting portion of terminal 63 is provided with a movable contact brush 64

adapted to be yieldingly held against terminal 43 by a coil spring 65. A terminal similar to terminal 63, but not shown in the interest of clarity, is provided directly above a portion of ring 47 for conducting high tension current from another or booster source of said ring and, hence, to the trailing one of the electrodes 51 and 52 for use primarily in starting the engine.

In order to minimize the possibility of flashovers between terminals 60 and the metallic casing 11, 12 and to obviate chafing of cables 61, 62 by reason of vibration, chamber 19 is preferably filled, as is also manifold 21, with a suitable insulating substance 66. The latter is preferably a solid and yet is of a pliable nature. One substance which has been found suitable is polymerized cashew nut-shell oil. The filling of chamber 19 and harness 21 also prevents moisture from entering or accumulating in said chamber and harness.

Filler 66 may also be used in a novel manner to lock set screws or bolts, which hold the various parts of the distributor and harness together, against accidental loosening or removal. For example, a portion of one of two engaging parts, such as manifold 21, may be cut away around a bolt 67, which secures the manifold to casing 11, to thereby form a recess 68 to receive the filling material, preferably around a threaded portion of the bolt. The latter is thereby yieldably held against turning and, hence, loosening of the bolt by vibration is effectively prevented in a very simple manner without rendering it unduly difficult to forcibly remove the same for purposes of disassembly.

Flashovers between casing 10, 11 and electrodes 59 within compartment 17 are also effectively avoided in a novel manner. The interior surfaces of casing members 19 and 11 are sprayed or otherwise coated, for this purpose, with a layer of insulating material 69.

Novel means are provided for ventilating compartment 17, said means being so constructed as to prevent rain and other foreign matter from being carried into the distributor by the air. Said ventilating means, in the form illustrated, are particularly adapted for installations wherein the axis of shaft 28 is inclined to the vertical and comprises an elongated tubular member 70. The latter is curved in the horizontal plane, as shown in the drawings, to fit the contour of casing member 10 and, when the distributor is mounted on an engine, member 70 is preferably tilted with respect to the vertical, so that one end is lower than the other end thereof, either by virtue of its installation in casing 10 or by virtue of the manner in which the casing is mounted on the engine.

The lower end of tube 70 is supported in a fitting 71 that has a hollow threaded portion 72 which extends through an opening in casing 10 and is secured in place by a nut 73. The hollow interior 74 of portion 72 serves to continuously connect the interior of tube 70 with the atmosphere. The upper end of said tube, the angular extent of the latter from end to end being something less than a semi-circle, is supported in a similar manner by a fitting 75 that has an opening 72 connecting tube 70 with chamber 17. Fitting 75 is provided with a threaded portion 77 that extends through the wall of casing 10 and is engaged by a nut 78. Compartment 17 is thus continuously connected with atmosphere through passage 74, curved tube 70 and passage 76. In traversing these passages, a substantial percent-

age of moisture and other foreign particles carried by the air are retarded and caused to drop to the bottom of tube 70 and hence to fall out through opening 74. It will, of course, be understood that more than one tube 70 may be provided and that casing 10 may, if desired, be cast with the ventilating passages therein.

In the operation of the distributor, as assembled in the drawings, high tension current is supplied from a magneto or other suitable source through cable 62, brush 64, terminal 43, contact disk 45 and conductor 55 to electrode 51. As the latter electrode is rotated in a clockwise direction, as viewed in Fig. 2 and in a manner heretofore fully described, the same will move beneath successive electrode points 59 in close relation thereto so that high tension current will flow from the moving electrode to the stationary electrodes and thence through conductors 57 and 61 to the spark plugs or other ignition devices of the engine with which the distributor is used. The high tension current is ordinarily supplied in timed impulses from an induction coil and it is accordingly necessary that electrode 51 pass below the various stationary electrodes 59 in timed relation to said impulses. The necessary positioning of the rotary unit may be effected for this purpose through the adjustable coupling comprising parts 28, 33 and 26 in a manner heretofore fully described.

High tension current may also be supplied to the same spark plugs by an auxiliary or booster source, such as for starting purposes, when the pistons in the respective cylinders of the engine are near their top dead-center positions. The booster current may be supplied by means of a brush contact through ring 47, disk 49, conductor 55, rotatable electrode 52 and electrodes 59. If the reverse direction of rotation is required in a particular engine, thereby making electrode 52 lead electrode 51, the current from the main source of supply may be readily directed from terminal 43 to electrode 52 and current from the booster source directed to electrode 51 by merely reversing the position of block 33 on plate 26. In order to insure proper assembly in the field, a positioning pin 79 may be provided in plate 26 for cooperation with a recess in block 33.

There is thus provided a novel ignition distributor for internal combustion engines which is housed in a novel manner in a metallic casing that may be rigidly and non-adjustably secured to the engine casing and which is provided with internal means for adjusting the movable electrodes with respect to the stationary electrodes thereof for timing purposes. Novel insulating parts are also provided, thereby minimizing the possibility of failure and reducing initial cost as well as cost of repair. There is also provided a novel rotatable electrode and terminal carrying means which may be readily adapted for rotation in either direction and wherein the electrodes, which are subject to wear and erosion during operation, may be readily and inexpensively replaced.

Although only a single embodiment of the invention has been illustrated and described in detail, it is to be expressly understood that the same is not limited thereto but that various changes may be made, particularly in the design and arrangement of parts illustrated without departing from the spirit and scope of the invention, as the same will now be understood by those skilled in the art. For a definition of the limits

of the invention, reference is had primarily to the appended claims.

What is claimed is:

1. In an ignition distributor, a rotatable member, a block of insulating material removably secured to said member for rotation therewith, said block having a pair of passages therethrough, one on each side of the axis of rotation thereof, a pair of terminals embedded in said block, a contact intermediate the ends of each of said passages, means connecting one of said terminals to the contact in one of said passages, and means connecting the other of said terminals to the contact in the other of said passages.

2. In an electric current distributor for internal combustion engines or the like, a rotatable member, a block of insulating material secured to said member for rotation therewith, said block being symmetrical with respect to a plane containing the axis of rotation of said member, a metallic terminal on said block, co-axial recesses in opposite sides of said block, contact means in said recesses, and means connecting said terminal to said contact means.

3. In an ignition distributor, a rotatable member, a block of insulating material removably secured to said member for rotation therewith, said block having a pair of passages therethrough, one on each side of the axis of rotation thereof, a pair of terminals embedded in said block, a contact intermediate the ends of each of said passages, means connecting one of said terminals to the contact in one of said passages, means connecting the other of said terminals to the contact in the other of said passages, a second block of insulating material mounted on said member and having a pair of parallel recesses in one face thereof, a pair of electrodes terminating in said parallel recesses and projecting beyond the periphery of said second block, said parallel recesses being coaxial with the corresponding passages in said first-named block, and means slidably extending into said recesses and passages for electrically connecting said electrodes with said contacts, said first-named block being adapted to be secured to said member in two positions whereby either of said passages may be in coaxial alignment with either of said recesses.

4. In an electric current distributor for internal combustion engines or the like, a rotatable member, a block of insulating material secured to said member for rotation therewith, said block being symmetrical with respect to a plane containing the axis of rotation of said member, a metallic terminal on said block, co-axial recesses in opposite sides of said block, contact means in said recesses, means connecting said terminal to said contact means, a second block of insulating material mounted on said member and having a pair of parallel recesses in one side thereof, a pair of electrodes on said second block projecting beyond the periphery thereof and each terminating at one end in one of said parallel recesses, one of the latter being coaxial with said coaxial recesses when said first block is secured to said member in one position and the other of said parallel recesses being coaxial with said coaxial recesses when said first-named block is turned through 180 degrees relative to said member, and means extending into said recesses for electrically connecting one of said electrodes to said contact means.

5. An ignition distributor comprising a three-

part metallic casing forming two chambers and including a base member, a central body member having a lateral wall constituting a common wall of said chambers and a cover, rotatable means journaled in said base member and including a driving member, a driven member, means for coupling said driven and driving members for angular adjustment relative to each other, an insulating block having a plurality of terminals thereon secured to said driven member, an insulating block having a plurality of electrodes thereon secured to said driven member and means for connecting said terminals to said electrodes, means mounted in said lateral wall for conducting high tension current to said terminals, and a plurality of stationary electrodes individually mounted on and insulated from said wall circularly arranged for successive cooperation with said first-named electrodes during rotation of the latter, said stationary electrodes extending from one of said chambers to the other.

6. Apparatus of the class described comprising a molded block of insulating material adapted to be mounted for rotation about an axis, said block having at least one pair of coaxial recesses perpendicular to a plane containing said axis of rotation, a terminal carried by said block, contact means in said recesses, and means connecting said terminal and the contact means in one of said recesses.

7. Apparatus of the class described comprising a molded block of insulating material adapted for rotation about an axis, said block having a pair of recesses in each of two opposed sides thereof, the axes of said recesses being perpendicular to a common plane containing said axis of rotation and said block being substantially symmetrical with respect to a plane containing said axis of rotation and parallel to the axes of said recesses, contact means in said recesses, a pair of terminals carried by said block, and means connecting one of said terminals to the contact means in one recess in each of said pairs of recesses, and means connecting the other of said terminals to the contact means in the other of said recesses.

8. A rotatable distributor finger for an ignition distributor comprising a support, two blocks of insulating material mounted on said support, each of said blocks having two electrical terminals thereon, and means interposed between said blocks for electrically connecting each of the terminals on one of said blocks to a different terminal on the other block, one of said blocks being reversible on said support for reversing the connections between said terminals without appreciably disturbing the balance of the distributor finger.
